UNITED STATES PATENT OFFICE.

GEORGE H. BRISTOL, OF TROY, NEW YORK, ASSIGNOR TO EARL & WILSON, OF TROY,
NEW YORK, A CORPORATION OF NEW YORK.

BEST AVAILABLE COPY COLLAR.

1,069,760.

Specification of Letters Patent. Patented Aug. 12, 1913.

Application filed November 7, 1911. Serial No. 658,924.

To all whom it may concern:

Be it known that I, George H. Bristol, a citizen of the United States, residing at Troy, county of Rensselaer, New York, have 5 invented certain new and useful Improvements in Collars, of which the following is a full, clear, and exact description.

My invention relates to improvements in the manufacture of collars, of the so-called 10 turn-down soft or unstarched variety, and has for its object to provide means whereby the collar will at all times when in use retain the desired form and at the same time be sightly in appearance.

Heretofore in the manufacture of soft 15 collars, it has been customary to provide fastening means whereby the lower front ends of the flaps were secured or held in position. The fastening means usually employed is to provide the ends of the flaps with button holes which coöperate with buttons on a strip of cloth or metal. After 20 the collar has been worn for even a very short time or when dampened or slightly 25 saturated with perspiration, it will tend to get out of shape, settle down and become wrinkled upon the neck of the wearer, thereby becoming most unsightly.

The object of my invention is to provide 30 a supporter where the ends of the collar are fastened to each other in such a way that the collar is prevented from wrinkling, sagging and from becoming otherwise distorted due to saturation or to a variety of other 35 causes.

A further object is to prevent the ends 40 of the collar from becoming unduly separated from each other which always results in an untidy appearance of the wearer.

Referring now to the drawings for a detailed description, and which form part of this application. Figure 1 is a front elevation showing the collar in position upon the band of a shirt, with the supporter in 45 position, the ends of which engage pockets which are shown in dotted lines. Fig. 2 is a front view with one corner of the outer portion folded back to show the position of the supporter. Fig. 3 is a side view showing the curvature of the arms. Fig. 3 shows 50 the supporter removed from the collar. Fig. 4 is a front view showing a modified form of supporter, in position. Fig. 5 is a view

of the modified form detached from the collar. Fig. 6 is a sectional view on the 55 line 6--6 of Fig. 5.

Referring to the drawings, wherein like characters refer to the same parts in all the views, the reference numeral 10 designates a shirt to the band of which is attached a collar which is made of soft material and is of the usual turned-over type. The collar shown is formed with the outer portion 11 and the inner portion or band 12. The band has any desired number of 60 button holes therein to receive the buttons 65 mounted on the collar band or secured to the shirt band.

From the description below, it will be clear that my invention, in its broadest 70 adaptation, is capable of being used with equal effect where one or a plurality of buttons are used. At the ends and on the inside of the lower corners of the outer portion of the collar, I provide suitable pockets 75 14, preferably triangular shaped, as shown, into which the extensions 16 of the supporter 15 are insertable. The pockets shown are formed by stitching pieces of cloth to the outer portion of the collar preferably of the same material as the collar. The supporter, for example the form shown at 15, when applied to the collar is shaped like an inverted V with the corner of the V preferably extending toward or abutting 80 the upper end corners of the outer portion of the collar where the said corners substantially meet when the collar is placed about the neck of the wearer. The ends of the arms of the V are provided with the 85 extension 16 which proceed vertically downward, then laterally, then upwardly, terminating in the loops 17. It will be noted that when the collar is attached to the neck band of the shirt in the usual manner one of the 90 arms with its extensions engages one of the pockets, while the other arm with its extension engages the other pocket. In assembling, one of the extensions is inserted into 95 one of the pockets, after the collar is fastened to the neck band of the shirt, as shown in Fig. 2, and the other extension is placed in the other pocket. The supporter is made of any suitable material but preferably of some metal, and I have found that wire 100 105 serves the purpose very admirably. If de-

sired it can be covered with fabric in order to enhance its appearance and to prevent the soiling of the collar, as shown in Fig. 3.

In Figs. 4, 5 and 6 I have shown a modified form of my invention wherein the arms of the supporter 18 are flattened and the extensions 19 formed of a solid flattened piece corresponding in thickness to the thickness of the arms to which they are attached. The interior side of this supporter, like that shown in the other views, is shaped to fit the curvature of the collar upon which it is placed. See Fig. 6 where the curvature of the extension 19 is clearly shown.

From the above description it will be seen that I have produced a supporter or stiffener for the front of the collar which not only prevents sagging, wrinkling, etc., but is very comfortable to the wearer. It possesses other capabilities, the most important of which is its simplicity, thereby reducing the cost thereof to a minimum, the ease with which it can be applied to the collar, and the ease with which the individual supporter may be adjusted to the different sizes and varieties of collars regardless of their height and the distance between the ends of the outer portion. Another feature of prime importance is the fact that it does not interfere in the least with the particular necktie that is used in conjunction with the collar.

While the embodiments of my invention herein described and shown on the annexed drawing are the preferred forms it is to be understood that I do not limit myself to the

exact structures shown as the device is capable of being embodied into other forms without, in any way, deviating from the true spirit and scope of my invention. 40

What I claim is:

1. In a collar of the turn-over type having an inner neck-band portion and an outer flap portion, said outer portion being in turned-over position, pockets on the inside 45 of the outer flap portion at the ends thereof, and a device bridging the space between the ends of the outer flap portion when the latter is in normal position on the neck of the wearer, said device having means engaging said pockets for maintaining the collar in normal position.

2. In a collar of the turn-over type having an inner neck band portion and an outer flap portion, pockets on the inside of the 50 outer flap portion adjacent the ends thereof, and means for maintaining the collar in normal position comprising a substantially V-shaped member having arms the ends of which are adapted to engage with said 55 pockets when the collar is in the turn-over position, said member bridging the space between the ends of the outer flap portion with the apex thereof extending upwardly 60 in proximity to the fold of said collar, substantially as described.

In testimony whereof I affix my signature in the presence of two subscribing witnesses.

GEORGE H. BRISTOL.
